UNITED STATES PATENT OFFICE.

OSBORN P. LOOMIS, OF SOMERVILLE, MASSACHUSETTS.

ELECTRIC LAMP.

SPECIFICATION forming part of Letters Patent No. 369,349, dated September 6, 1887.

Application filed January 5, 1887. Serial No. 223,447. (No model.)

To all whom it may concern:

Be it known that I, OSBORN P. LOOMIS, of Somerville, county of Middlesex, and State of Massachusetts, have invented an Improvement 5 in Electric Lamps, of which the following description, in connection with the accompanying drawings, is a specification, like letters on the drawings representing like parts.

My invention relates to electric lamps, and 10 has for its object to improve and simplify the general construction of arc lamps, and more especially to provide a simple and efficient feed mechanism for the carbons.

In accordance with my invention I employ 15 a single-bar electro-magnet differentially wound with coarse and fine wire and provided at its ends with pole-pieces, the lower pole-piece having a beveled or inclined block attached to or forming part of it. The upper 20 pole-piece has pivoted to it an elbow-lever having an arm connected to the clutch mechanism, to be described, and a second arm to a dash-pot, while a third arm of the said lever is extended to near the lower pole-piece and 25 forms an armature for the electro-magnet. The arm of the elbow-lever which forms the armature of the electro-magnet preferably has secured to it an insulated contact-terminal, which co-operates with a second contact-terminal, 30 preferably insulated from a second electro-magnet of smaller dimensions, the said co-operating contact-terminals acting, when brought together, as will be described, to cut out the lamp from the line-circuit.

35 Other features of my invention will be pointed out in the claims at the end of this specification.

Figure 1 is a side elevation of a sufficient portion of my improved lamp to enable my invention to be understood; Fig. 2, an end view 40 of Fig. 1, looking toward the right; Fig. 3, a section of Fig. 1 on line $x-x$; Fig. 4, a diagram showing the manner of connecting the lamp in circuit; Fig. 5, a modification to be referred 45 to, and Fig. 6 a detail to be referred to.

The upper portion of the frame of my improved lamp is composed of an electro-magnet consisting of a bar, a , preferably of wrought or malleable iron, which is differentially wound 50 with coarse wire, a' , and fine wire, a'' , and two pole-pieces, a^3 a^4 , preferably of wrought or malleable iron, attached to the ends of the bar a ,

as shown, by screw b , (see dotted lines, Fig. 1,) the said pole-pieces having secured to them by the screws b caps b' of insulating material, 55 the lower portion of the said lamp being of ordinary construction. The caps b' and pole-pieces a^3 a^4 are provided with centrally-disposed openings for the passage of the upper-carbon carrier, b^2 .

The pole-piece a^3 of the electro-magnet, as herein shown, is provided with lugs b^3 , to which is pivoted an elbow-lever, b^4 , having one arm, b^5 , secured to the piston-rod b^6 of a piston of a dash-pot, b^7 , the latter being supported, as 55 shown, by a rod, b^8 , secured to or forming part of the bottom of the dash-pot, the said rod being fastened by screw b^9 to the pole-piece a^4 . Another arm, c , of the elbow-lever is extended from the pole-piece a^3 to near a beveled or inclined block, c' , attached to or forming part of 70 the pole-piece a^4 , the arm c forming an armature for the electro-magnet.

The armature c , as shown in Fig. 1, has secured to it an insulating-block, f , provided 75 with a contact-terminal, f' , which co-operates with a contact-terminal, f^3 , secured to but insulated from the core of an electro-magnet, f^4 , the contact-terminal f' being connected to the positive wire and the contact-terminal f^3 with 80 the coil of the electro-magnet f^4 , the said coil being connected to the negative wire, as clearly shown in Fig. 4. The elbow-lever b^4 also has a third arm, c^2 , which is connected by the rod c^3 to one end of a clutch-lever, c^4 , (shown in 85 Fig. 3 as a single piece provided with an opening in the body portion m , through which the carbon-carrier is passed,) the other end of the said clutch-lever sliding upon an upright rod, c^5 , fastened, as shown, to the pole-piece 90 a^4 and provided with an adjustable block, c^6 .

The body portion of the clutch-lever through which the carbon-carrier is passed is curved or bent so that the clamping points or surfaces, as 2 3, are not in line with each other, 95 one being above the other, as shown in Fig. 6.

By making the halves of the body portion of the clutch out of line with each other I obviate the wedging action upon the carbon-carrier of the old-style ring-clutch, thus obtaining a quick and easy release and re-engagement of the carbon-carrier, thereby obtaining a steady feed of the carbon, and consequently 100 a uniform light.

In the operation of my improved lamp, and as thus far described, the current enters the lamp through the coarse wire, a' , one end of the said wire being connected, as shown in Fig. 4, with the positive pole and the other end with the upper-carbon carrier, the current passing through the carbons and to the negative pole of the lamp, as indicated by the arrows, part of the current flowing through the differential fine wire, a'' , attached to the coarse wire, a' . The current passing through the coarse wire, a' , magnetizes the bar a and its pole-pieces a^3 a^4 , and also the block c' , the latter attracting its armature c , thereby turning the elbow-lever on its pivot and lifting the clutch c^4 through the rods c^2 c^3 , thus establishing the arc. As the arc increases in length, the current passing through the differential wire a'' , having one end connected to the coarse wire, a' , and its other end to the negative pole of the lamp, is increased and acts to neutralize the action of the main current upon the electro-magnet.

The neutralization of the effect of the main circuit upon the electro-magnet by the differential current permits the armature c to be withdrawn from the block c' by the dash-pot, or it may be by a spring, 5, fastened to the arm b^3 . As the armature c recedes, the clutch c^4 is lowered, and the long arm of the clutch-lever strikes on the adjustable stop c^6 and releases the bind of the surfaces 2 3 upon the carbon-carrier, thus permitting the same to feed downward, the said clutch releasing the carbon-carrier very gradually and smoothly, thus effecting a gradual and easy feed of the carbon.

When the arc becomes abnormally long by the carbon sticking or for other cause, the current of the differential wire neutralizes the effect of the current in the coarse wire upon the core a , and the armature c is moved backward by the dash-pot acting upon the lever b^3 , as described, to close the cut-out circuit through the contact-terminals f' f'' , the latter being kept together by the attractive force of the magnet f^4 for the armature c .

The lamp will remain cut out of circuit, as in the case of a broken carbon, until a new carbon has been placed in position and in contact with the lower carbon, thus closing the main circuit, whereupon the current passes through the coarse wire, a' , and magnetizes the core a and pole-pieces a^3 a^4 and block c' , the latter attracting the armature c and breaking the cut-out circuit and lifting the carbon to establish the arc.

By constructing the block c' beveled or inclined the armature is made to approach or travel up the said block slower and easier than if the said block presented a flat upright surface, that part of the incline passed over by the end of the armature acting to retard the movement of the said armature by opposing or pulling against, as it were, the attraction of that part of the block which is in front of the said armature.

Referring to Fig. 5, I have shown the ar-

mature c as wound with wire, 20, which in diagram Fig. 4 is the wire 21. The end of the wire 20 forms the contact-terminal f' , which co-operates with the second terminal, f'' , the latter being insulated from a post or upright, 22. It will thus be seen that the magnet f^4 is dispensed with, and the armature c becomes an electro-magnet when the circuit is closed at the terminals f' f'' . The electro-magnet thus formed serves to maintain a sure and positive closing of the cut-out circuit.

I claim—

1. An electric lamp comprising a magnet 80 having its core wound differentially and provided at its ends with pole-pieces, combined with a lever having an arm extended from one pole-piece toward the other pole-piece to constitute an armature for the said magnet, and having a second arm connected with a clutch mechanism to lift a carbon and establish the arc as the armature is attracted by one of the said pole-pieces, substantially as described.

2. An electric lamp comprising a magnet 90 having its core wound differentially and provided at its ends with pole-pieces, a beveled or inclined block on one of said pole-pieces, combined with a lever having an arm extended from one pole-piece to near the said inclined block to constitute an armature for the said magnet, and having a second arm connected with a clutch mechanism to lift a carbon and establish the arc as the armature travels up the inclined block, substantially as 95 described.

3. An electric lamp comprising a single magnet having its core wound differentially and provided at its ends with pole-pieces, a beveled or inclined block on one of said pole-pieces, a lever having an arm extended from one pole-piece to near the said inclined block to constitute an armature for the said magnet, a second arm of said lever connected to a clutch mechanism to lift a carbon and establish the arc as the end of the armature travels up the inclined block, combined with a third arm of the said lever, and with means connected to the said third arm to move the armature away from the inclined block as the magnetism of 115 the core is diminished, substantially as described.

4. An electric lamp comprising a single magnet having its core wound differentially and provided with pole-pieces combined with the elbow-lever b^4 , having an arm, c , constituting an armature for the said magnet, and provided with a contact-terminal, combined with a second terminal co-operating with the terminal on the armature, as and for the purpose specified.

In testimony whereof I have signed my name to this specification in the presence of two subscribing witnesses.
